UNITED STATES PATENT OFFICE

2,496,425

RAILWAY CAR COUPLER

Harry H. Wolfe, Columbus, Ohio, assignor to The Buckeye Steel Castings Company, Columbus, Ohio

Application October 9, 1945, Serial No. 621,249

19 Claims. (Cl. 213—109)

1

This invention relates to improvements in railway car couplers, and more particularly to an improved interlocking coupler for freight service.

There are at the present time two standard couplers in general use on the railways of the United States; the A. A. R. Standard Type "E" coupler which has been standard since 1931 and originally used on all new passenger and freight cars; and the recommended A. A. R. Type "H" Tightlock coupler which was made a standard for new passenger cars in 1944. The original Tightlock coupler known as the Type "T" was used on passenger cars from 1936 until the Type "H" was made a standard in 1944.

The Tightlock coupler has many advantages over the Type "E" coupler for passenger cars due to the tight fit in the contours of two coupled Type "H" couplers (no free slack in pull or buff) and its interlocking features which act to align the two opposing Type "H" couplers both vertically and horizontally within certain predetermined limits. The details of these couplers are, of course, familiar to the art.

A new type of coupler is now being proposed for use in freight service. This coupler will incorporate the general features of the Tightlock passenger coupler with the exception of the tight contour. A small amount of free slack will be provided in the contour so as to eliminate the machining which is done on the Type "H" Tightlock coupler to obtain an absolutely tight contour.

The proposed interlocking freight coupler will couple with all existing standard couplers such as the old M. C. B. coupler, Type "D" coupler, Type "E" coupler, and the Tightlock Type "T" and Type "H" couplers.

The proposed interlocking freight coupler has aligning wings similar to the tightlock passenger coupler and which were designed to intermesh with the aligning wings of the tightlock coupler.

All freight cars have air and signal lines located on the right hand side facing the end of the car. These train lines terminate at each end of the car in angle cocks for opening and closing the lines, and air hoses are connected to the angle cocks and hose couplings are fastened to the free end of the hoses. The angle cocks have certain locations on the ends of the cars so that the air hoses are all standard lengths. However, the angle cock locations may vary within certain limits but numerous cars have the angle cocks located outside these limits and have operated satisfactorily.

In coupling a car equipped with the proposed

interlocking coupler to existing cars equipped with "D" or "E" couplers, it has been found that the aligning wing on the knuckle side of the proposed interlocking coupler interferes with the angle cocks or train lines on numerous existing cars and to change the locations of the angle cocks on all existing cars would be a tremendous undertaking.

In order to eliminate this interference without changing the location of the angle cocks, the applicant has conceived the idea of removing entirely the lower portion of the aligning wing on the knuckle side of the interlocking coupler and replacing it with aligning surfaces and abutments centrally located at the bottom of the coupler which arrangement will clear all train lines. The new structure will perform all the functions of the portion removed on the knuckle side of the coupler and also will perform the additional functions of increasing the strength of the front face of the coupler by tying the guard arm to the pulling lugs and in case of failure through the shank of existing couplers, such as the M. C. B., "D", and "E" couplers, the shelf extending forward of and below the central portion of the contour will prevent the broken coupler from falling to the rail and possibly causing a derailment.

The above features are not limited to an interlocking freight coupler, and may be applied to existing tightlock couplers by the use of an adapter casting incorporating the above features, which can be welded to the underside of existing tightlock couplers.

With these and other objects in view, the invention consists of certain novel features of construction and operation, as will be more fully described and particularly pointed out with reference to the accompanying drawings, in which:

Fig. 1 is a top plan view of a coupler made in accordance with the invention.

Fig. 2 is a similar view of the same, facing the coupler shown in Fig. 1 to illustrate the manner in which a pair of couplers mate.

Fig. 3 is a side elevation of one of the couplers.

Fig. 4 is a similar view looking from the side opposite that shown in Fig. 3.

Fig. 5 is a front elevational view of one of the couplers.

Fig. 6 is a diagrammatic view taken through the guard arm and aligning wing pocket and through the bottom shelf portions of a pair of the couplers shown approaching coupling position. The section of the coupler at the left of this figure is taken on line 6a—6a of Fig. 5, and

the section of the coupler at the right of Fig. 6 is taken on the line 6b—6b of Fig. 5.

Referring to the drawings, 7 designates a coupler having a shank 8 rigidly united with a head 9, preferably integral therewith. In accordance with the invention, the head is provided at one side with a forwardly projecting guard arm 10, and at the opposite side with an aligning wing pocket 11. Between these parts, there is a contour 12 comprising a wide vertically disposed groove or recess 13, arranged at one side of forwardly projecting bearing portions 14 in which the vertical shaft 15 of the pivoted knuckle 16 is journaled, said knuckle being swingable toward and away from the groove 13, as indicated in dot and dash lines, for the purpose of clasping the knuckle of another coupler.

In keeping with the present invention, the guard arm 10 (Figs. 1 and 2) is of known construction, and terminates in a wedge nose 17 having forwardly converging lateral surfaces 18 and 19 adapted to cooperate with lateral walls 20 and 21 of the aligning wing pocket 11 of another coupler, in bringing a pair of tight-lock couplers or the like into mating relation. The guard arm also has top and bottom forwardly converging surfaces 22 and 23 (Figs. 4 and 6) designed to engage upper and lower converging surfaces of the aligning wing pocket of a tight-lock coupler (not shown) when the two couplers are coming together.

In accordance with my invention, the lower half of the aligning wing pocket 11 is omitted (Figs. 5 and 6) but the top sloping surface 22 of a guard arm of another coupler is adapted to slidably engage a rearwardly and downwardly sloping surface 24 provided at the bottom of the room 25 of the pocket of my coupler. As is customary in tight-lock couplers, a forwardly projecting lug 26 having a substantially vertical abutment surface 26a, is arranged at the roof of the pocket 11 and is designed to enter a cavity 27 at the top of the guard arm 10 of another coupler and abut against a vertical surface 21a of the latter, when the two come into mating relation. The guard arm has a second similar cavity 28 (Fig. 4) at its bottom for the reception of a lug like the lug 26 of a standard tight-lock coupler (but arranged at the bottom of the pocket) when the present coupler is used therewith.

In the invention, as before mentioned, the bottom portion of the pocket 11 is eliminated, and as shown in Fig. 5, the bottom edge of the rear wall of the pocket is inclined downwardly and toward the medial portion of the coupler head, as indicated at 29, so as not to interfere with train air lines, etc.

A depending extension 30 projects from the bottom of the coupler head and is rigidly united therewith, so as to form a horizontal shelf 31 at one side and closely adjacent to the central portion of the bottom of the head, which shelf is spaced from the bottom 32 of the knuckle 16 to provide a horizontally disposed cavity 33 for the reception of the bottom portion of a falling knuckle or the like, which can land on the shelf.

The edge of the shelf is positioned at the front of the coupler head and is concaved, as shown at 34 (Figs. 1, 2 and 5), for the reception of the lower bearing 14 of the knuckle shaft of a mating coupler, in the event one coupler should happen to be lower than the other when they come together. A transverse vertical portion 34a of said edge is positioned to abut a like surface of

another similar coupler when the two are in coupled condition. It may be seen from Figs. 1 and 2 that the shelf obstructs the lower end of the groove 13 but as it is spaced from the bottom of the knuckle, a gauge (not shown) may be readily moved downwardly through the groove when the knuckle is in closed position and may afterwards be removed from between the knuckle and shelf.

Immediately below the shelf, I arrange a forwardly projecting lug 35 positioned at one side of the longitudinal vertical plane of the coupler, and I provide the front of this lug with an upwardly and rearwardly inclined ramp 36 designed to cooperate with the depending flange 37 or bottom of the shelf of another similar coupler to lift the latter onto the top of lug 35 when the couplers are coming together (if such lifting is necessary) to insure that the front surface 34a of the shelf flange of one coupler will come into abutting relation with the front surface 34a of the flange of the other coupler, as indicated in Fig. 6. When this takes place, the front surface 26a of the aligning wing pocket 11 of one coupler will come into abutting relation with the corresponding surface 27a of the guard arm 10 of the other coupler.

As may be seen from Figs. 1 and 2, when the couplers are to be brought into mating relation, the knuckles are in dotted line positions, and as the couplers move toward one another, the nose 17 of the guard arm of one coupler will enter the aligning wing pocket 11 of the other, and owing to the complementary surfaces, they will function to guide the parts into mating relation. Simultaneously, the lugs 35 (Fig. 6) at the bottoms of the couplers will cooperate with the lower edges 37 of the front flanges of the coupler shelves so as to further insure proper mating, and as is customary, the knuckles of the two couplers will be brought into clasped position by any preferred means (not shown).

The depending extension 30 and the parts thereof below the weld joints shown in Figs. 3, 4 and 5 may be formed as a separate casting as hereinabove indicated. Such an adapter casting may be welded along the lines shown in Figs. 3, 4 and 5 to the under side of existing tight-lock couplers or may be formed as a separate part in constructing new couplers and welded to the under side of the head.

From the foregoing, it will be understood that my improved coupler will interlock with a coupler of identical construction or with a standard tight-lock coupler because the latter will have an aligning wing pocket functioning for the same purposes as the pocket 11, but provided with a bottom to cooperate with the parts 23 and 28 of the guard arm of the opposing coupler. My improved coupler may also be interlocked with standard couplers which do not have any gathering or aligning wings, as there is nothing to interfere with the knuckle of such a coupler interlocking with the knuckle of my improved coupler. It will also be apparent, in the event that a coupler should fall while coupled to my improved coupler, its knuckle will land on the shelf 31 so that the couplers will remain coupled and thereby prevent derailment or the like.

While I have disclosed what I now consider to be a preferred embodiment of the invention in such manner that the same may be readily understood by those skilled in the art, I am aware that changes may be made in the details dis-

closed without departing from the spirit of the invention as expressed in the following claims:

What I claim and desire to secure by Letters Patent is:

1. A coupler of the character described comprising a head having a forwardly projecting guard arm at one side thereof and a rearwardly extending aligning wing pocket at the opposite side thereof adapted to receive the guard arm of a similar coupler, the pocket being of materially less depth than the guard arm and having an open bottom, and means carried by the head to force a similar coupler to become aligned with said first-mentioned coupler during the coupling operation.

2. A coupler of the character described comprising a head having a forwardly projecting guard arm at one side thereof and a rearwardly extending aligning wing pocket at the opposite side thereof adapted to receive the guard arm of a similar coupler, the pocket being of materially less depth than the guard arm and having an open bottom, a knuckle pivotally connected to the head for swinging movement between the guard arm and pocket, and means carried by the head to force a similar coupler to become aligned with said first-mentioned coupler during the coupling operation.

3. A coupler of the character described comprising a head having a forwardly projecting guard arm at one side thereof and a rearwardly extending aligning wing pocket at the opposite side thereof adapted to receive the guard arm of a similar coupler, the pocket being of materially less depth than the guard arm and having an open bottom, said pocket having a roof provided with a bottom surface inclined rearwardly and downwardly, and means carried by the head to force a similar coupler to become aligned with said first-mentioned coupler during the coupling operation.

4. A coupler of the character described comprising a head having a forwardly projecting guard arm at one side thereof and a rearwardly extending aligning wing pocket at the opposite side thereof adapted to receive the guard arm of a similar coupler, the pocket being of materially less depth than the guard arm and having an open bottom, said pocket having opposite side walls, the inner surfaces of which converge toward the rear of the pocket, and means carried by the head to force a similar coupler to become aligned with said first-mentioned coupler during the coupling operation.

5. A coupler of the character described comprising a head having a forwardly projecting guard arm at one side thereof and a rearwardly extending aligning wing pocket at the opposite side thereof adapted to receive the guard arm of a similar coupler, a knuckle pivotally connected to the head between the guard arm and pocket, a shelf extending forwardly of the medial portion of the front of the head and spaced vertically from the knuckle, and a lug projecting forwardly from the shelf and adapted to slidably engage the shelf of a similar coupling.

6. A coupler of the character described comprising a head having a forwardly projecting guard arm at one side thereof and a rearwardly extending aligning wing pocket at the opposite side thereof adapted to receive the guard arm of a similar coupler, said head having at the front thereof a contour between the guard arm and pocket forming a vertical groove and bearings, a knuckle journaled in the bearings and movable

toward and away from the groove, a shelf extending forwardly of the medial portion of the head, spaced downwardly from the knuckle and extending beneath the lower end of the groove, and a lug projecting forwardly from the bottom portion of the shelf and adapted to underlie the shelf of a similar coupler.

7. A coupler of the character described comprising a head having a forwardly projecting guard arm at one side thereof and a rearwardly extending aligning wing pocket at the opposite side thereof adapted to receive the guard arm of a similar coupler, said head having at the front thereof a contour between the guard arm and pocket forming a vertical groove and bearings, a knuckle journaled in the bearings and movable toward and away from the groove, a shelf extending forwardly of the medial portion of the head, spaced downwardly from the knuckle and extending beneath the lower end of the groove, and a lug projecting forwardly from the bottom portion of the shelf and adapted to underlie the shelf of a similar coupler; said lug being provided with a ramp inclined upwardly and rearwardly from its front end.

8. A coupler comprising a head provided at the front thereof with a knuckle pivotally mounted for swinging movement about a vertical axis, a shelf arranged at the bottom portion of the front of the head and spaced downwardly from the knuckle, and a lug projecting forwardly from the bottom portion of the shelf at the medial portion of the head and offset to one side of the longitudinal vertical plane of the coupler, and adapted to underlie the shelf of a similar coupler when the couplers are in coupled position.

9. A coupler comprising a head provided at the front thereof with a knuckle pivotally mounted for swinging movement about a vertical axis, a shelf arranged at the bottom portion of the front of the head and spaced downwardly from the knuckle, and a lug projecting forwardly from the bottom portion of the shelf at the medial portion of the head and offset to one side of the longitudinal vertical plane of the coupler, and adapted to underlie the shelf of a similar coupler when the couplers are in coupled position, said lug being provided with a ramp inclined upwardly and rearwardly from the front end thereof.

10. In a coupler of the character described, a coupler head provided at one side with an aligning wing pocket arranged mainly on the upper half of the coupler and having a roof, rear wall and inner and outer side walls, the outer and rear walls being of materially less depth than the coupler head and the lower end of the pocket being open, and means carried by the head to force a similar coupler to become aligned with said first-mentioned coupler during the coupling operation.

11. A coupler of the character described comprising a head having a forwardly projecting guard arm at one side thereof and a rearwardly extending aligning wing pocket at the opposite side thereof adapted to receive the guard arm of a similar coupler, the pocket being of materially less height than the guard arm and having an opening bottom, said head having at the front thereof a contour between the guard arm and pocket forming a vertical groove and upper and lower bearings arranged at one side of the groove, a knuckle journaled in the bearings and movable toward and away from the groove, a shelf at the bottom of the head extending forwardly of the

medial portion of the latter, spaced downwardly from the knuckle and projecting beneath the lower end of the groove, and a lug projecting forwardly from the bottom portion of the shelf and adapted to underlie the shelf of a similar coupler.

12. In a coupler of the knuckle type, a head provided at its bottom portion with a forwardly extending shelf, a lug projecting from the bottom portion of the shelf and adapted to underlie the shelf of a similar coupling, said shelf being provided with a front edge portion arranged in a substantially vertical plane approximately perpendicular to the longitudinal axis of the coupling, a substantially horizontal upper surface on said lug merging with said edge portion of the shelf, and an inclined surface on the lug sloping downwardly in proceeding forwardly from said horizontal surface.

13. A coupler of the character described comprising a head having a forwardly projecting guard arm at one side thereof and a rearwardly extending aligning wing pocket at the opposite side thereof adapted to receive the guard arm of a similar coupler, the pocket being arranged mainly on the upper half of the head, being of materially less depth than the guard arm and having an open bottom, and means carried by the head to force a similar coupler to become aligned with said first-mentioned coupler during the coupling operation.

14. In a coupler of the knuckle type, a head provided at its bottom portion with a forwardly extending shelf, a lug projecting from the bottom portion of the shelf and adapted to underlie the shelf of a similar coupling, said shelf being provided with a front edge portion arranged in a substantially vertical plane approximately perpendicular to the longitudinal axis of the coupling, a substantially horizontal surface on said lug merging with said edge portion of the shelf, said lug being provided with a ramp inclined upwardly and rearwardly from the front end thereof, a guard arm on the coupler head, and means providing a guard arm receiving pocket on the coupler head.

15. A coupler of the character described comprising a head provided at its bottom portion with a forwardly extending shelf having at least two front edge portions, one edge portion being arranged in a substantially vertical plane approximately perpendicular to the longitudinal axis of the coupler and the other edge portion being concaved, and a lug projecting from the bottom portion of the shelf and adapted to underlie the shelf of a similar coupling.

16. In a coupler of the knuckle type, a head provided at its bottom portion with a forwardly extending shelf having at least two front edge

portions, one edge portion being arranged in a substantially vertical plane approximately perpendicular to the longitudinal axis of the coupler and the other edge portion being concaved, a lug projecting from the bottom portion of the shelf adapted to underlie the shelf of a similar coupling, and said lug being provided with a ramp inclined upwardly and rearwardly from the front end thereof, for engaging under the shelf of a similar coupling.

17. A coupler of the character described comprising a head having a forwardly projecting guard arm at one side thereof and a rearwardly extending aligning wing pocket at the opposite side thereof adapted to receive the guard arm of a similar coupler, the pocket being of materially less height than the guard arm and having an open bottom, and means at the front of the bottom of the head adapted to cooperate with a similar coupler to force the coupler to become aligned during the coupling operation.

18. A coupler of the character described, comprising a head having a forwardly projecting guard arm at one side thereof and a rearwardly extending wing pocket at the opposite side thereof adapted to receive the guard arm of a similar coupler, said wing pocket being arranged mainly at the upper half of the coupler and having a roof, a rear wall and inner and outer side walls, the outer and rear walls being of materially less depth than the coupler head and the lower end of the pocket being open, and means at one side and closely adjacent the central portion of the bottom of the head adapted to cooperate with a similar coupler to force the couplers to become aligned during the coupling operation.

19. An adapter for a coupler head, comprising a shelf adapted to be arranged at the bottom portion of the front of the head, and a lug projecting forwardly from the bottom portion of the shelf and adapted to underlie the shelf of a similar coupler provided with the adapter when the couplers are in coupled position, said lug being provided with a ramp, inclined upwardly and rearwardly from the front end thereof.
